CLAIM

The ornamental design for a head garment, as shown and described.

DESCRIPTION

FIG. 1 is a perspective view of a head garment showing our new design, shown in a used condition on a human head in broken lines;

FIG. 2 is another perspective view of FIG. 1, shown in an unused condition;

FIG. 3 is a rear view of FIG. 2, shown in an unfolded position;

FIG. 4 is top view of FIG. 2;

FIG. 5 is a left side view of FIG. 2;

FIG. 6 is a front view of FIG. 2; and,

FIG. 7 is a right side view of FIG. 2.

The even dashed broken lines in the figures of 1-7 and the human head in FIG. 1 form no part of the claimed design.
